UNITED STATES PATENT OFFICE.

WILLIAM J. KLEMM, OF CHICAGO, ILLINOIS, ASSIGNOR TO RUDA MANUFACTURING COMPANY, OF CHICAGO, ILLINOIS, A CORPORATION OF ILLINOIS.

WINDOW STRUCTURE.

Application filed October 7, 1925. Serial No. 60,947.

My invention relates to window structures, particularly that type in which the window sash, in addition to being vertically slidable, is adapted to be swung on horizontal axes to 5 serve as ventilation deflectors and also to be in better position to be washed from the inside of the building.

The important object of my invention is to provide improved simple and efficient means 10 for securely locking the sash against accidental vertical movement when it has been swung to inclined position. In accordance with my invention I provide friction or 15 brake mechanism which, when the sash is vertical and parallel with the runways, is rendered inoperative so that the sash may readily slide, but which, as soon as the sash is swung to inclined position, is released and is then controlled by the weight of the 20 sash or the counterweight to exert friction or braking pressure against the walls of the sash runway to securely lock the sash against sliding movement in the runway when the sash is in inclined position. The 25 braking mechanism is released for operation or rendered inoperative by means of cam mechanism controlled by the swinging movement of the sash.

The above and other features of my invention are incorporated in the window structure shown on the drawings, in which—

Fig. 1 is a front elevational view of a window frame with the sash therein;

Fig. 2 is an enlarged sectional view on plane 2—2 of Fig. 3;

Fig. 3 is a sectional view on plane 3—3 of Figs. 1 and 2;

Fig. 4 is a sectional view on plane 4—4 of Fig. 3.

As best shown in Figs. 2 and 3, the window frame which receives the upper and lower sashes S and S' is constructed of sheet metal and comprises the sill section 10, the head section 11, and the side sections 12.

The side frames have the inner and outer channels 13 and 14 for the lower and upper sashes, respectively. These channels are lined by weather strip frames 15 and 16 of sheet metal and within these weather strip frames are the runner structures 17 and 18 to which the lower and upper sashes, respectively, are attached. As shown, the sash stiles are of sheet metal formed to cooperate with the weather strip frames to

provide weather tight joints. The sash 55 runners are each connected to a chain or chord 19 passing over a pulley 20 and connected at its other end with a sash weight W, the sash weights being accommodated in the side frames 12. The sash weights 60 balance the combined weight of a sash and its supporting runner structures.

The support of the sashes on the runners and the operation and construction of the locking or braking mechanism, is clearly 65 shown in Fig. 3, in which the lower sash is shown swung inwardly and the upper sash is vertical. Each sash at each of its lower corners has a pivot pin 21 which is held and journaled in the lower end of the respective 70 runner frames, these runner frames being of channel shape, as clearly shown in Fig. 2. Above each pivot connection a supporting bar 22 is pivoted at its outer end to the respective side of the sash by means of a preferably detachable pivot pin or other suitable device 23. At its inner end each bar is pivoted to a pin 24 which extends into the 75 respective runner frame through a longitudinally extending slot 25 and secured to a cam plate 26. The cam plate is of a width to fit between the side walls of the runner frame and at its upper end has the inclined 80 cam or wedge surface 27. With this arrangement, as the sash is swung, the arms or bars 22 will shift the cam plates vertically in the runner frames. In each runner frame above the slot 25 therein is a brake 85 shoe plate 28 having the deflection 29 forming a brake shoe for passing through the notch or opening 30 in the adjacent side wall 90 of the runner frame to exert friction against the adjacent wall of the runner receiving channel 13 and 14 to thus brake or lock 95 vertical movement of the runner frame in the channel. The brake shoe plate is pivoted by a pin or rivet 31 to the web of the runner frame so that as the plate revolves around the pivot the brake shoe extension will be withdrawn from or projected through the opening 30. At one side of the pivot 31 a link 32 is pivoted to the brake shoe plate, the link serving as a fastening for the chain or chord which travels over the respective 100 sash weight w.

Pull on the chord or chain relative to the respective runner frame will cause the brake shoe plate to swing and carry its shoe 29

outwardly through the opening 30, and therefore when a sash hangs against the pull of the sash weights, the tendency will be for the brake shoe plates to be swung into 5 braking position. The lower rear edge of the brake shoe plate forms a cam surface 33 against which engages the cam or wedging surface 27 of the cam plate which is shifted by the swinging movement of the sash. As 10 the sash is swung into its vertical position, the cam plates at the opposite sides thereof come into camming or wedging engagement with the brake shoe plates and these plates are then swung in direction to bring in their 15 brake shoes through the openings 30 and away from the window frame surface so that the sash with its runner frame may then be readily vertically shifted in the window frame. However, as soon as a sash has 20 been swung sufficiently to disengage its cam plate from the brake shoe plates, then the pull of the chords or chains on these brake shoe plates will cause them to swing into 25 braking or interlocking engagement with the window frame so that the runner frames with the sash supported thereon will be locked against vertical movement in the window frame. Thus braking or locking 30 mechanism which is normally inoperative is released for operation when a sash is 35 swung to inclined position.

After the lower sash has been raised a distance to clear the weather ridge 34 on the 35 sill 10, and the upper sash has been dropped a distance to clear the channels in the head 11, either or both of the sashes may be swung inwardly, in which position they are readily accessible from the inside of the building 40 for washing and cleaning. The length of the bars 22 and the extent of the slots 25 determines the limit of swing of the sash. In the arrangement shown, the sash may be 45 swung to positions at right angles with the window frame. It may be desirable to hold one of the sashes, preferably the lower sash, in only slightly inclined position to direct incoming ventilating air upwardly into the 50 room and prevent direct blowing into the room of the air. I therefore provide supporting pins or lugs 35 on the opposite sides of the window frame against which the lower sash, a short distance above its pivot point, may rest so that the sash will be held 55 in only slightly inclined position, when the sash is raised only a short distance vertically. By raising the sash higher, its inclination can be increased, and as soon as the lugs 35 are cleared, the sash can be swung 60 into horizontal position. In Fig. 3 full lines show the lower sash in horizontal position and dotted lines show it in slightly inclined position and resting against the lugs 35.

As before stated, the connection between 65 the sash and the bars 22 is preferably de-

tachable. The connection of the pivot pin 21 with the lower end of the runner frame is also preferably detachable in order that the sash may be readily installed and also that they may be readily removed for repair 70 purposes. The pivot connection between the sash and the runner frame is shown in Figs. 3 and 4. The webs of the runner bars have each a longitudinal notch 36 extending from the lower edge thereof, and into this notch 75 the respective pivot pin 21 is inserted. A plate 37 having a longitudinal slot 38 is then inserted between the side walls of the runner frame with the slot end abutting against the pin so as to confine the pin between the 80 end of the notch 36 and of the slot 38. The plate 37 is held in place by a nut 39 which extends between the side walls of the runner frame and receives a screw 40 extending 85 through the web of the runner frame, the inner end of the plate 37 having the flanges 41 which abut against the upper edges of the nut and so lock the plate 37 in locking 90 position. When it is desired to remove the sash from the window frame, the screws 40 are withdrawn, whereafter the nut can be removed and the plate 37 withdrawn so that the sash pivot pins can then be disengaged 95 from the notches 36. Then when the bars 22 are detached from the sash, the sash will be free to be removed. The sash can as readily be inserted into the window frame.

Along the sides of the lower sash at its inner side the stiles are offset, as indicated at 42, to leave space 43 between the sash and the respective runner frame for the accommodation of the supporting bars 22. The upper sash has similar offsets 44 to leave the spaces 45 for the supporting bars 22 for such sash. On the outer side, the vertical stiles of the lower sash have the vertical grooves 46 for receiving the inner edges of the weather strip structures 16. The outer sash has similar grooves 47 for receiving the outer edges of the weather strip frame. The inner end 50 of the weather strip structure 15 is engaged by the offset parts 42 of the inner sash, while the intermediate sections 51 of the weather strip structure 16 engage with the offset portions 44 of the upper sash. These engagements of the weather strip structures with the sash will not interfere with the swinging movement of the sash. When the sashes are in vertical position, this weather stripping engagement will securely seal the space between the sash and the runner frames.

I thus provide a window structure in which the sash can be readily raised and lowered, and readily swung inwardly to inclined position. The locking or braking mechanism for locking the sash structures against vertical movement when inclined, are equally efficient for any angle of inclination of the sash.

I do not desire to be limited to the exact construction, arrangement and operation shown and described, as modifications can be made which will still come within the scope of the invention.

5 I claim:—

1. In a window structure, the combination of a window frame having upright side channels, runners slideable in said channels, a window sash pivoted to said runners for swinging movement thereon, brake shoe structures on said runners, window weights and chords therefor connected with said brake shoe structures and tending to move 10 said structures into frictional engagement with the window frame whereby to prevent sliding movement of said runners, and means controlled by the swinging movement of said sash for preventing operation of 15 said brake shoe structures when said sash is in closed position and for releasing said structure for operation when the sash is swung to open position.

2. A window structure comprising a window frame having upright side channels, runners slideable in said channels, a window sash pivoted to said runners for swinging movement relative thereto, pivoted locking members in said runners, window weights 20 and chords therefor connected with said locking members and adapted to swing them into locking engagement with the window frame to thereby prevent sliding movement of said runners in said channels, and means 25 controlled upon swinging movement of said sash for preventing operation of said locking members when said sash is swung to closed position and for permitting operation of said members when said sash is swung to open 30 position.

3. In a window structure, the combination of a window frame having upright side channels, runners slideable in said channels, a window sash pivoted to said runners for swinging movement, interlocking mechanism 45 for preventing sliding movement of said runners in said frame channels, window weights, chords extending from said weights and connected with said interlocking, mechanism and tending to cause operation thereof, and means controlled upon swinging movement of said sash for rendering said interlocking mechanism inoperative when the sash is swung to closed position and for releasing it for operation when the sash 50 is swung into open position.

4. In a window structure, the combination of a window frame having side channels, runners slideable in said channels, a window sash pivoted to said runners for swinging movement thereon, locking mechanism carried by said runners for cooperating with the window frame to prevent sliding movement of said runners, window weights, 55 chords extending from said weights and

connecting with said locking mechanism, the pull of said chords on said locking mechanism tending to move said locking mechanism to operative position, and a cam member 60 slideable within said runners and controlled by the swinging movement of said sash, said cam member being displaced from said locking mechanism when said sash is swung to open position whereby said locking mechanism may then become operative to lock 65 said runners against sliding movement, and said cam members being brought into cooperation with said locking mechanism to shift said locking mechanism to inoperative position when said sash is swung into closed 70 position.

5. In a window structure, the combination of a window frame having upright side channels, running slideable in said channels, a window sash pivoted to said runners for 75 swinging movement, locking mechanism within said runners for cooperating with the window frame to lock said runners against sliding movement, means tending to move said locking mechanism into operative position, controlling members shiftable in said 80 runners, connections between said shiftable members and said sash for causing shifting movement of said members when said sash is swung, said shifting members cooperating with said locking mechanism to make it inoperative when said sash is swung to closed position, and releasing said locking mechanism to permit operation thereof 85 when said sash is swung to open position.

6. In a window structure, the combination of a window frame having upright side channels, runners slideable in said channels, a sash pivoted to said runners for swinging 90 movement, locking mechanism, means tending to actuate said locking mechanism to lock said runners to said frame to prevent sliding movement of said runners, cam members within said runners, said runners having slots extending longitudinally, bars pivoted to said sash and connected with said 95 cam members through said slots whereby swinging movement of said sash will cause longitudinal movement of said cam members in said runners, said cam members having camming engagement with said locking mechanism to render said locking mechanism inoperative when said sash is swung to closed position and said cam members 100 being released from said locking mechanism to permit operation thereof when said sash is swung to open position.

7. In a window structure, the combination of a window frame having side grooves, runners slideable in said grooves, a window sash pivoted to said runners for swinging movement thereon, said runners having side 105 openings, levers pivoted to said runners and having brake shoe extensions adjacent to 110 said openings, means tending to swing said 115

120

125

130

levers to project said brake shoe extensions through said openings into frictional engagement with the window frame to thereby lock said runners against sliding movement, 5 and means controlled when said window sash is swung to swing said levers to withdraw their brake shoe extensions from the window frame when said sash is swung to closed position and to release said levers for 10 operation when the sash is swung into open position.

8. In a window structure, the combination of a window frame having side channels, runners slideable in said channels, a window sash, pivot pins extending from said sash, 15 said runners having each a slot at its lower end, said pivot pins being received in said slots to thereby pivot said sash for swinging movement relative to said runners, and de-

tachable means for locking said pins in said 20 slots.

9. In a window structure, the combination of a window frame having side channels, runners slideable in said channels, a window sash, pivot pins extending from said sash, 25 said runners having each a slot at its lower end, said pivot pins being received in said slots to thereby pivot said sash for swinging movement relative to said runners, a locking plate for each runner having a slot 30 for receiving the respective pin and for co-operating with the slot to form a bearing for said pin, and means for securing said plate in locking position.

In witness whereof, I hereunto subscribe 35 my name this 30th day of September, 1925.

WILLIAM J. KLEMM.
